CONVERTIBLE TABLE AND BENCH

Peter J. Abler, Hollydale, Calif.

Application July 7, 1951, Serial No. 235,601

8 Claims. (Cl. 155—124)

1

The present invention relates to furniture, and its general object is to provide a convertible article of furniture which is selectively useable as either a combined bench and table unit or as a back-supporting type bench.

Combined bench and table units of the type employing a single frame to support a table and a bench therefor in fixed relation are utilized extensively in parks, gardens, patios, and the like. Although these units provide a rigid structure which is economical of construction, it is a well known fact that the bench member thereof becomes quite uncomfortable when occupied for any extended period of time. This discomfort is primarily caused by the fact that such benches generally do not include a back rest. The lack of a back rest is necessitated as a practical matter by the obstacle to ingress and egress such an element would create, the conventional combined bench and table unit generally being designed to accommodate a plurality of persons sitting in side-by-side relationship.

Another factor contributing to the uncomfortable nature of the bench member of the conventional bench and table unit is the horizontal disposition of the seating surface thereof with respect to the ground. Such an arrangement is required in order that the torso of an occupant's body be disposed substantially normal to the surface of the table top. In view of these disadvantages, a person will object to occupying such benches for more than a comparatively short period of time. Instead, if such is available, he will soon seek a bench or chair having a back rest, which bench or chair will also preferably be formed with a seat which slopes downwardly from its front end.

In the light of the foregoing remarks, it is a major object of the present invention to provide a novel convertible article of furniture which incorporates the desirable features of both a combined bench and table unit and of a back-supporting type bench.

It is another object of the present invention to provide an article of furniture of this type which is of simple construction and economical to manufacture.

It is a further object of the present invention to provide a convertible article of furniture of this type which is extremely rigid and sturdy both as a combined bench and table unit and as a back-supporting type bench.

It is yet another object of the present invention to provide a novel article of furniture of this type which may be quickly and easily converted from a combined bench and table unit to a back-

2

supporting type bench and vice versa, without the use of any tools and without the addition or subtraction of any parts.

Other objects and advantages of the present invention will be apparent from the following detailed description, taken in conjunction with the accompanying drawings, wherein:

Figure 1 is a broken front view of a preferred embodiment of the novel convertible article of furniture of the present invention, the parts thereof being arranged so as to form a combined bench and table unit;

Figure 2 is a side view of said article taken along line 2—2 of Figure 1;

Figure 3 is a side view of said article, partly in section, taken along line 3—3 of Figure 1;

Figure 4 is a side view of said article, partly in section, taken from the same point as Figure 3 after the parts of said article have been rearranged so as to form a back-supporting type bench;

Figure 5 is a fragmentary perspective view showing a detail of construction of said article;

Figure 6 is an enlarged fragmentary side view showing a latch utilized in the construction of said article;

Figure 7 is an enlarged fragmentary view of said latch taken along line 7—7 of Figure 6;

Figure 8 is a side view of a second embodiment of the present invention; and

Figure 9 is a perspective view showing a manner whereby a pair of the articles of furniture of the present invention may be arranged for use.

Referring to the drawings, and particularly to Figures 1 to 3 thereof, the preferred embodiment of the present invention broadly comprises a pair of longitudinally spaced vertical frames, generally designated 10 and 10a; a rectangular table member, generally designated 12, mounted by the upper portion of the frames; and a rectangular seat, generally designated 14, also mounted by the frames. As shown arranged in these three figures, the foregoing parts form a combined bench and table unit. When arranged as shown in Figure 4, however, these same parts form a back-supporting type bench, the table member 12 then constituting a vertically inclined back rest for the sloping seat 14.

As shown clearly in Figures 1 and 2, the frames 10 and 10a are identical and will preferably be formed from a single length of steel tubing bent so as to define a base element 22, a rear element 24, a short top element 26, a main diagonal 28, a sub-diagonal 30 and a front element 32. The ends of this length of tubing are welded, as indicated at

34 and 36, whereby the various elements and diagonals constitute an integral structure. Although it is not essential that steel tubing be utilized in forming the frames, such material has been found very satisfactory because of its favorable strength-to-weight ratio. Of course these frames may also be formed of wood or concrete.

The table member 12 may be formed of any suitable material such as wood, metal or plastic, and its exact dimensions may vary in accordance with the number of persons to be accommodated. Thus, this table member may be of considerable length whereby a large number of persons may be accommodated, or it may be made of such length as to accommodate only a single person. Of course, if the table member is to be of considerable length, it may be necessary to employ more than two frames in order to obtain a rigid structure. The seat 14 may be formed of the same material as the table member 12 and will preferably be of the same length as this member but of less width.

It is contemplated that the table member 12 be pivotally mounted by the frames 10 and 10a whereby it may be rotated about a longitudinal axis from its position of Figure 3 to that of Figure 4. To this end, as shown particularly in Figure 5, a short horizontally disposed sleeve 38 may be rigidly affixed, as by welding, to each of the frames at the juncture of the top element 26 and the main diagonal 28. Also, there is shown rigidly secured to the under side of the table member 12 adjacent each of the frames, generally L-shaped cross braces 40 and 40a. These cross-braces include an integral bracket 42 near their mid-portion, which brackets and the depending portion 44 of the cross-braces adjacent thereto are formed with aligned holes 46 and 48, respectively. A pivot pin or bolt 50 is used to connect the cross-braces 40 and 40a to the sleeves 38 and 38a; a nut 52 being used to secure this bolt 50 in place. By this arrangement the table member 12 is pivotally mounted for rotation about a longitudinal axis extending through the bolts 50.

The seat 14 is preferably mounted upon a pair of generally U-shaped tubular supports, generally designated 54 and 54a, which supports are pivotally secured at their lower ends to the frames 10 and 10a. These supports are shown rigidly attached to the under side of the seat 14 by means of bolts 56 extending through an ear 58 formed at the upper end of one of the legs of the supports, and by welding 60 joining the upper end of the other leg of the supports to cross-bars 62 and 62a; the latter being secured to the under side of the seat adjacent the frames 10 and 10a. The lower end of each of the supports 54 and 54a are formed with integral bifurcations 64 and 64a which include aligned holes 66. These bifurcations are adapted to straddle upstanding lugs 68 and 68a rigidly attached, as by welding, to the base elements 22 and 22a of the two frames. Each of the lugs is formed with a hole 70 whereby a pin 72 may be utilized to pivotally interconnect the bifurcations and the lugs. Accordingly, it will be seen that the seat 14 is mounted for movement along an arc having a radius equal to the length of the supports 54 and 54a. Preferably, in order to restrain movement of the seat in a direction normal to the frames, the under side of the seat will mount a pair of guides 74 and 75, and 74a and 75a arranged to straddle the sub-diagonals 30 and 30a of the frames.

The present invention contemplates novel

means for rigidly maintaining the table member 12 and the seat 14 in their proper relative positions, both when arranged to form a combined bench and table unit and when arranged to form a back-supporting type bench. It is another feature of this invention that movement of the table member 12 from its horizontally disposed position of Figure 3 to its vertically inclined position of Figure 4 may simultaneously effect movement of the seat 14 from its horizontally disposed position of Figure 3 to its sloping position of Figure 4.

To this end there may be provided pivotally interconnected levers 77, 79, 79a, and 81, 81a shown disposed between the table member, the seat and the frames. The upper levers 77 are each pivotally connected at their topmost end to the forward portion of the cross-braces 40 and 40a, as by pins 76. The lower levers 79 are pivotally connected at their lowermost ends to the main diagonals 28 of the frames 10 and 10a, as by pins 78. These upper and lower levers are pivotally interconnected at their opposite ends by pins 80. The short levers 81 are each pivotally connected at their rear end to the intermediate portion of the lower levers by pins 82, and at their front ends to the rear portion of the seat cross-bars 62 and 62a by pins 84.

Referring again to Figure 3, at such time as the table member 12 and the seat 14 are disposed so as to form a combined bench and table unit, it is contemplated that the upper and lower levers be locked against relative rotation about their pivotally interconnected ends. By this means these two levers will constitute a rigid support extending between the forward portion of the table member and the base of the two frames whereby the table member will be restrained against pivotal movement with respect thereto. It is further contemplated that when it is decided to move the table member to its vertically inclined position of Figure 4, the upper and lower levers be freed for relative rotation about the pins 80. At this time the front of the table member may be moved downwardly until the under side of its cross-braces 40 and 40a abut the front surface of the main diagonals 28 of the frames.

In order to releasably lock the upper and lower levers against relative rotation about the pins 80, there may be provided a latch member, generally designated 86. The preferred form of latch 86 is shown in detail in Figures 6 and 7, and comprises a generally circular boss 88 having an elongated handle 90 integrally formed therewith. The boss 88 is eccentrically pivotally mounted adjacent the lower end of the upper lever 77 by means of a stud bolt 92, which bolt is shown as having its threaded end secured within a bore 94 formed in the boss. To engage the latch 86 so as to lock the levers against relative movement, these levers will first be aligned as shown in Figure 3. Thereafter, the handle 90 may be rotated in a clockwise direction about the axis of the bolt 92 from the position indicated by dotted lines in Figure 6 to the solid line position of this figure. This action will bring the convex lower surface 96 of the boss into abutting relationship with a concave recess 98 formed at the upper extremity of the lower lever 79. With the latch 86 so disposed the upper and lower levers are positively interlocked. To disengage the latch whereby the levers will be freed for relative movement, it is only necessary to lift the handle 90 so as to rotate the boss counterclockwise about the axis of the

bolt 52, as indicated by the arrow in Figure 6. Such action will withdraw the boss surface 96 from the recess 98 so that the lower lever 79 may be pivotally moved relative to the upper lever, as indicated by the dotted lines and the arrow in Figure 6.

It should be noted that although the preferred type of latch shown in the drawings is recommended, various other forms of latching devices may be utilized without departing from the scope of the present invention. It should also be noted that the type of latch 86 described above, although shown in Figures 6 and 7 in conjunction with only one set of levers 77 and 79, will also be used with the other set of levers 77a and 79a.

As set forth hereinabove, the upper and lower levers 77 and 79, when interlocked by the latch 86 will rigidly support the table member 12 in its horizontally disposed position of Figures 1 through 3. At this time the short lever 81 cooperates with the levers 77 and 79 to rigidly maintain the seat 14 in a horizontally disposed position. This relationship is clearly shown in Figure 3, and referring thereto, it will be seen that no movement of the seat toward or away from the table member may take place so long as the levers 77 and 79 are interlocked. With the latch 86 disengaged, however, as the table member is pivoted to its vertically inclined position of Figure 4, the seat 14 by virtue of its interconnection with the lower lever 79 through the short lever 81, will be simultaneously moved to its sloping position shown in this figure.

Once the table member 12 and the seat 14 have assumed their respective positions of Figure 4, they will be rigidly maintained therein by virtue of their interconnection through the levers 77, 79 and 81. The reason for this will become apparent if it is realized that once the seat 14 has been moved rearwardly to its sloping position of Figure 4, its center of gravity will lie some distance to the rear of the pivot pin 72. Thus, the seat will be acted upon by a counterclockwise component of force with respect to the pivot pin 72. This component of force will be transferred to the lower lever 79 by means of the short lever 81 so as to tend to cause counterclockwise rotation of the lower lever about its pivot pin 78. By virtue of its pivotal interconnection with the lower lever, the upper lever will thus be acted upon by a downwardly directed force. This downwardly directed force when transferred by the upper lever to the front portion of the cross-brace 40 by means of pin 76 serves to maintain the under side thereof in engagement with the front of the fixed frame diagonal 28. By this arrangement the table member 12 and the seat 14 will be maintained in proper position to form a back-supporting type bench until such time as it becomes desirable to rearrange them so as to form a combined bench and table unit. At this time, as the table member is pivoted counterclockwise about pivot bolt 50 to a horizontal position, the seat 14 will be simultaneously urged to a horizontal position. The latch 86 may then be latched, as described previously hereinbefore.

Referring now to Figure 8, there is shown a side view of a second embodiment of the present invention, the major components of which are of wooden construction. These components include a pair of longitudinally spaced frames, generally designated 100 (only one of which is shown); a table member, generally designated 102, pivotally mounted by the upper portion of the frames as by a hinge 103; and a seat, generally designated

104, also mounted by the frames for pivotal movement from a horizontal to a sloping position. The table member 102 is shown in Figure 8 in solid lines disposed in a horizontal position so as to form the table portion of a combined bench and table unit, and is shown in dotted lines disposed in a vertically inclined position so as to form the back rest of a back-supporting type bench. Likewise, the seat 104 is shown in solid lines disposed in a horizontal portion and in dotted lines disposed in a sloping position to correspond with the two positions of the table member. In this embodiment of the invention movements of the table member 102 and the seat 104 are independent inasmuch as they are not interconnected. Thus, the table member may be rigidly maintained in its horizontal position by means of a single lever 106 disposed between the under side thereof and the lower portion of the frame 100. Preferably, this lever will be pivotally attached at its lower end to the frame by means of a pin 108 and will be releasably secureable to the cross-brace 110 of the table member, as by a removable pin 112. In order to free the table for rotation to its vertically inclined position, it is only necessary to release the upper end of the lever 106 by withdrawing pin 112 whereby this lever may be pivoted toward the rear of the frame 100, as indicated by the dotted arrow. The table member may then be rotated clockwise until its under side abuts the front of the frame diagonal 101. The removable pin 112 may be inserted through a hole 113 formed in the upper portion of the rear frame member so as to support the upper end of the lever 106 thereon. The seat is shown secured at its front portion to the upper end of a support 114, which support is pivotally secured at its lower end to the base of the frame 100, as by a pin 116. The support 114 may be rigidly maintained in its solid line position by a removable pin 118 which is insertable through aligned holes formed in the support and in the transverse diagonal 120 of the frame. To free the seat for movement to its sloping position, it is only necessary to remove the pin 118 whereby the seat may be pivoted rearwardly until its under side rests upon the upper surface of the frame diagonal 120. It will be evident that both the table member 102 and the seat 104 will remain in their dotted line positions under the influence of gravity.

Referring now to Figure 9, there is shown a pair of the convertible articles of furniture of the present invention disposed in back-to-back relationship. When utilized in this manner, the persons occupying the two seats may face each other so as to facilitate conversation while dining, for example, or while playing cards. Thereafter, if it should become desirable to witness a sport, television program, or some other form of entertainment, the two bench and tables may be disposed end-to-end and converted into back-supporting type benches.

It will be apparent that the aforescribed invention permits the construction of a single article of furniture which will embody the advantages of both a combined bench and table unit and a back-supporting type bench. Accordingly, there is made possible a considerable saving of space. This latter feature will be especially important where such an article of furniture is desired for a private garden or patio. Moreover, a convertible article of furniture built in accordance with the present teachings will be compact and attractive in appearance.

Various modifications and changes may be made with respect to the forgoing description without departing from the spirit of the invention or the scope of the following claims.

The invention claimed is:

1. A convertible article of furniture useable as either a combined bench and table unit or as a back-supporting type bench, comprising: a frame; a table member having a generally flat upper surface pivotally mounted on the upper portion of said frame for rotation about a horizontal axis; a seat carried by said frame; means disposed between said table member and said frame for selectively locking said table member against rotation about said axis whereby it may be maintained either with its upper surface in a substantially horizontally disposed position so that said table member may form the table component of a combined bench and table unit, or with said surface in a vertically inclined position whereby said table member may form the back rest component of a back-supporting type bench; and means carried by said frame for selectively maintaining said seat in either a substantially horizontal position whereby it may cooperate with said table member to form the bench component of a combined bench and table unit, or in a position sloping downwardly in a direction toward said table member whereby said seat may cooperate with said table member to form the seat component of a back-supporting type bench.

2. A convertible article of furniture useable as either a combined bench and table unit or as a back-supporting type bench, comprising: a pair of spaced upright frames; an elongate table member having a generally flat upper surface, said table member being pivotally mounted by the upper portion of said frames for rotation about a longitudinal axis; a first lever pivotally connected at one of its ends to said table member at a point spaced transversely of said axis; a second lever pivotally connected at one of its ends to a lower portion of one of said frames, said levers being pivotally interconnected at their other ends; a latch carried by one of said levers, said latch including a convex portion selectively insertable within a concave surface formed in the other said lever so as to rigidly interlock said levers whereby said table member may be supported with its upper surface in a substantially horizontally disposed position, said levers when not interlocked allowing said table member to be rotated about said axis until its under side abuts parallel vertically inclined surfaces formed on said frames; a seat mounted by the upper portion of a pair of supports, each of said supports being pivotally secured at its lower portion to one of said frames whereby said seat is adapted for pivotal movement about a longitudinal axis parallel to said other longitudinal axis; and a lever pivotally connected at one of its ends to said seat and at its other end to one of the other said levers whereby rotation of said table member so as to move its upper surface from a substantially horizontally disposed position to a vertically inclined position will effect simultaneous pivotal movement of said seat from a substantially horizontally disposed position to a position sloping downwardly in a direction toward said table member.

3. A convertible article of furniture useable as either a combined bench and table unit or as a back-supporting type bench, comprising: a pair of spaced upright frames; an elongate table member having a generally flat upper surface,

said table member being pivotally mounted on the upper portion of said frames for rotation about a longitudinal axis; a first lever pivotally connected at one of its ends to said table member at a point spaced transversely of said axis; a second lever pivotally connected at one of its ends to a lower portion of one of said frames, said levers being pivotally interconnected at their other ends; a latch, said latch being formed with a boss eccentrically pivotally mounted to one of said levers whereby a convex portion of said boss may be selectively inserted within a concave surface formed in the other of said lever adjacent the end thereof pivotally interconnected to the latch-carrying lever so as to rigidly interlock said levers whereby said table member may be supported with its upper surface in a substantially horizontally disposed position, said levers when not interlocked allowing said table member to be rotated about said axis until its under side abuts parallel vertically inclined surfaces formed on said frames; a seat carried by the upper portion of a pair of supports, each of said supports being pivotally secured at its lower portion to one of said frames whereby said seat is adapted for pivotal movement about a longitudinal axis parallel to said other longitudinal axis; and a lever pivotally connected at one of its ends to said seat and at its other end to one of the other said levers whereby rotation of said table member so as to move its upper surface from a substantially horizontally disposed position to a vertically inclined position will effect simultaneous pivotal movement of said seat from a substantially horizontally disposed position to a position sloping downwardly in a direction toward said table member.

4. A convertible article of furniture useable as either a combined bench and table unit or as a back-supporting type bench, comprising: a frame having a vertically inclined portion; a table member having a generally flat upper surface pivotally mounted by the upper portion of said frame for rotation about a horizontal axis; a seat carried by said frame; a first lever pivotally connected at one of its ends to said table member at a point spaced from said axis; a second lever pivotally connected at one of its ends to said frame, said levers being pivotally interconnected at their other ends; and, a latch carried by one of said levers, said latch including a convex surface selectively insertable within a concave surface formed in the other lever so as to rigidly interlock said levers whereby said table member will be maintained with its upper surface in a substantially horizontal disposed position so that said table member may form the table component of a combined bench and table unit, said levers when not interlocked allowing said table member to be rotated about said axis until said surface assumes a vertically inclined position wherein the underside of said table member abuts the vertically inclined portion of said frame whereby said table member may cooperate with said seat to form the back rest component of a back-supporting type bench.

5. A convertible article of furniture useable as either a combined bench and table unit or as a back-supporting type bench, comprising: a frame; a table member having a generally flat upper surface pivotally mounted on the upper portion of said frame for rotation about a horizontal axis; a seat carried by said frame for pivotal movement about a horizontal axis parallel to said other horizontal axis; means disposed be-

tween said frame and said table member for selectively locking said table member in a horizontally disposed position; means carried by said frame for selectively maintaining said seat in either a horizontally disposed position, or in a position sloping downwardly in a direction toward said table member; and, means interconnecting said table member and said seat whereby rotation of said table member from its horizontally disposed position to a downwardly sloping position will effect simultaneous pivotal movement of said seat from its horizontally disposed position to its downwardly sloping position.

6. A convertible article of furniture useable as either a combined bench and table unit or as a back-supporting type bench, comprising: a frame having a vertically inclined portion; a table member having a generally flat upper surface pivotally mounted on the upper portion of said frame for rotation about a horizontal axis; a seat carried by said frame for pivotal movement about a horizontal axis parallel to said other horizontal axis; and, a plurality of pivotally interconnected levers attached to said frame and disposed between said table member and said seat whereby rotation of said table member from a substantially horizontal position to a vertically inclined position will effect simultaneous pivotal movement of said seat from a substantially horizontal position to a position sloping downwardly in a direction toward said table member, the underside of said table member abutting the vertically inclined portion of said frame when said table member is disposed in its vertically inclined position.

7. A convertible article of furniture useable as either a combined bench and table unit or as a back-supporting type bench, comprising: a frame having a vertically inclined portion; a table member having a generally flat upper surface pivotally mounted on the upper portion of said frame for rotation about a horizontal axis; a first lever pivotally connected at one of its ends to said table member at a point spaced from said axis; a second lever pivotally connected at one of its ends to said frame, said levers being pivotally interconnected at their other ends; a latch carried by one of said levers, said latch including a convex surface selectively insertable within a concave surface formed in the other said lever so as to rigidly interlock said levers whereby said table member will be supported with its upper surface in a substantially horizontally disposed position, said levers when not interlocked allowing said table member to be rotated about said axis until said surface assumes a vertically inclined position wherein the underside of said table member will abut the vertically inclined portion of said frame; a seat carried by said frame for pivotal movement about

5
10

a horizontal axis parallel to said other horizontal axis; and a lever pivotally connected at one of its ends to said seat and at its other end to one of the other said levers whereby rotation of said table member so as to move its upper surface from a substantially horizontally disposed position to a vertically inclined position will effect simultaneous pivotal movement of said seat from a substantially horizontally disposed position to a position sloping downwardly in a direction toward said table member.

8. A convertible article of furniture useable as either a combined bench and table unit or as a back-supporting type bench, comprising: a frame formed with vertically inclined diagonals; a table member having a generally flat upper surface pivotally mounted on the upper portion of said frame for rotation about a horizontal axis; a first lever pivotally connected at one of its ends to said table member at a point spaced from said axis; a second lever pivotally connected at one of its ends to said frame, said levers being pivotally interconnected at their other ends; a latch, said latch being formed with a boss eccentrically pivotally mounted to one of said levers whereby a convex portion of said boss may be selectively inserted within a concave surface formed in the other said lever so as to rigidly interlock said levers whereby said table member will be supported with its upper surface in a substantially horizontally disposed position, said levers when not interlocked allowing said table member to be rotated about said axis until said surface assumes a vertically inclined position wherein the underside of said table member abuts the diagonals of said frame; a seat carried by said frame for pivotal movement about a horizontal axis parallel to said other horizontal axis; and a lever pivotally connected at one of its ends to said seat and at its other end to one of the other said levers whereby rotation of said table member so as to move its upper surface from a substantially horizontally disposed position to a vertically inclined position will effect simultaneous pivotal movement of said seat from a substantially horizontally disposed position to a position sloping downwardly in a direction toward said table member.
